UNITED STATES PATENT OFFICE.

SAMUEL A. MENCZER, OF FORT WORTH, TEXAS.

WINDOW CASING.

Application filed June 27, 1925. Serial No. 39,927.

To all whom it may concern:

I've it known that I, SAMUEL A. MENCZER, a citizen of the United States, and a resident of Fort Worth, in the county of Tarrant and State of Texas, have invented certain new and useful Improvements in Window Casings, of which the following is a specification.

My invention relates to improvements in window casings, and is of particular value in connection with metal windows of the so-called "solid metal" type.

The principal objects of the invention are to provide a window construction organized so that the sashes and associated parts may be readily removed and installed when access to the sash cords and weights is desired; to provide a construction in which the detachable portions of the window casings are inconspicuously and rigidly secured in position; to provide a construction of simple design which shall be relatively inexpensive to manufacture, install and maintain, and in general to provide a neat, rugged and efficient window casing of the character referred to.

A further object of the invention is to provide a removable unit jamb for heavy windows, of solid or one-piece metal construction and means for rigidly and conveniently securing the same in position.

On the drawings, Fig. 1 is a vertical sectional view of a window casing embodying my invention, with the upper and lower sashes assembled therein in closed positions.

Fig. 2 is a similar view but illustrating the manner of removing and installing the sashes.

Fig. 3 is a horizontal cross sectional view taken on the section line 3-3 of Fig. 1, and

Fig. 4 is a fragmentary vertical sectional view taken on the staggered section line 4-4 of Fig. 1.

Referring to the drawings in detail, 5 designates the window frame which is preferably of sheet metal construction and set in the wall 6 of a building at a window opening, which wall has the usual sill 7. The top and sides of the frame 5 have in-turned flanges 8 and are shaped or formed with an inner jamb or bead 9, a central jamb or parting strip 10 and an outer jamb or stop 11 providing guideways 12 and 13 for the upper and lower sashes 14 and 15 respectively. The inner bead or stop 9 is

continued around the bottom of the window frame 5 but the parting strip 10 and stop 11 terminate at the outwardly sloping or inclined sill portion 16, provided to give the necessary drainage. However, in order to insure protection against inclement weather, the bottom portion of the frame 5 at the guideway 13, is provided with a raised portion or shoulder 17 producing a step-like construction with the bead 9.

The upper and lower sashes may be of standard construction and are shown constructed of metal and slidably in the guideways of the jamb construction. The lower part of the upper sash 14 has its frame bent to provide a pocket or groove 18 into which a depending flange 19, at the top of the lower sash 15, extends, in order to provide a weather-tight joint between the sashes when closed. The bottom of the lower sash also has a depending flange 20 which fits over the shoulder 17 to additionally render the construction weather-proof. The sides of the frame 5 unlike the top and bottom which are open, are closed by the wall 21, as seen in Fig. 3, and have a partition 22 forming chambers for accommodating the sash weights 23 and sash cords 24.

In order to permit convenient installation and removal of the sashes and access to the sash cords and weights when desired, the sides of the window frame or casing are provided with removable sections or jamb units 25 which extend to the outer stop 11 from the inner side of the frame or casing, and from a point adjacent the sill to a distance considerably above the top of the lower sash so as to readily accommodate the height of the sashes therein. In order to accommodate these removable units, the inner faces of the sides of the frame or casing are recessed or cut out as indicated at 26 on lines diverging inwardly, so as to provide a tapering recess to permit the correspondingly tapered jamb units or sections 25 to readily enter therein and be displaced therefrom. In order to mount the removable jamb units in position, the sides of the sash frame are open at the inside as indicated at 27, the inner edge being directed inwardly to form a flange 28 and the outer edge being flanged or directed outwardly as at 29 and then bent to provide the stop 11 which is of permanent construction throughout its length.

The inner edge of the metal forming the stop 11 is directed outwardly and then in-

wardly to form a groove 30 for snugly receiving the adjacent edge portion 31 of the removable jamb section or unit 25 and the free edge 32 is flared or curved inwardly to engage cross-members or braces 33 which connect the flanges 28 and 29, as indicated at 34. By having the bent portions 32 engage the horizontal cross-members or strips 33, the edges 31 are tightly held in the grooves 30 to provide weather-tight joints, and this may be further carried out by providing a tortuous weather-strip 35 at the parting strip 10 and between the same and the U-shaped sides of the sashes. These sashes are also provided with removable frames 36 held by screws or other fasteners 37 to removably secure the window panes in place.

As shown in the drawings, any number of the cross-members 33 may be provided, preferably one to every three feet of height, although this is optional and may be varied. As indicated in the drawings, the top and bottom cross-braces are shown overlapping the joints between the permanent and removable jamb units and the inner ends of the strips are directed laterally inwardly, as indicated at 38, for connection with the overlapping angularly bent portions 39 of the inner bead 9 of the removable jamb units as by means of screws or other fasteners 40.

It will thus be seen that the sashes may be readily installed by first sliding the same into the respective guideways of the removable jamb units and then the removable jamb units with the sashes therein are inserted in the recesses or cut-out portions at the sides of the window frame or casing, after which the screws 40 are applied. This places the sashes in line with the guideways owing to the alignment of the respective parts 9, 10 and 11 forming the beads or strips of the frame, when the sashes may be freely slid into open or closed positions. In disassembling or removing the sashes, it is only necessary to reverse the operation by moving the sashes within the confines of the removable jamb units or sections 25, as illustrated in Fig. 2 of the drawings, and by removing the fasteners 40 either prior to or after so positioning the sashes, when the sashes may be displaced from the window casing or frame with the removable jamb units by sliding the latter inwardly from the position shown in Fig. 1 to displace the same from the window frame in the manner indicated in Fig. 2 of the drawings.

The preferred construction requires the use of three screws at each side of the window casing to secure the removable jamb units in position, three of the cross-members or braces 33 being likewise employed. While the parts of the casing, sashes and removable sections or jamb units are preferable

of fourteen-gauge sheet metal and the braces of heavier metal, say one-eighth inch stock and preferably about one inch wide, it is to be understood that I am not limited to these specific measurements or proportions and that the same may be widely varied, according to the particular demand. It is also apparent that a window construction such as described is so organized that the sashes and associated parts may be readily assembled or installed and removed for replacement or repair, and that by reason of the open portions 27, convenient access may be had to the sash cords or chains and weights when the removable jamb units are removed together with the sashes. Moreover, since the joints between the tapered jamb units and the permanent portions of the casings of corresponding cross-section terminate at the inside of the outer stop or bead 11, a storm-proof window is provided in combination with the joints between the sashes and between the bottom sash and the sill of the window casing or frame.

While I have shown and described my invention in a preferred form, I am aware that various changes and modifications may be made without departing from the principles of my invention, the scope of which is to be determined by the appended claims.

I claim as my invention:

1. In a metal window, the combination of the outer casing, inner and outer sashes, and a removable jamb unit provided with guides for both sashes and detachably secured to the outer casing.

2. In a window, the combination with a casing, a sash mounted in the casing and a removable jamb unit at one side of the casing corresponding in cross-section to the cross-section of the sash-receiving portion of the casing and detachably secured therein.

3. In a window construction, a casing having sash guides, sashes mounted in the casing, said casing having jamb sections with removable portions of a height to accommodate the sashes therein and adapted to be displaced from the jamb sections to permit displacement of the sashes therewith from the casing, and means to secure said removable jamb portions in position at the inside of the casing.

4. In a metal window, the combination of an outer casing having permanent beads at the outside, the sides of the casing having cut-outs between said beads and the inner side of the casing, jamb units removably secured in said cut-outs and the casing above and below the same being formed with beads providing sash guides, and sashes mounted in said guides and adapted to be removed from the casing with the units when moved into the confines of said units.

5. The combination with a window frame having sash guides and being open trans-

versely at their inner portions, braces secured across said inner portions from the opposite sides of the frame, said frame having unbroken outer beads extending vertically along and across said open portions, sashes mounted in the guides, jamb sections removably mounted in the sides of the frame at said open portions and forming continuations of the guides of the frame, and means to secure the removable jamb sections to the braces.

6. The combination with a window frame having sash guides and being open at their inner sash-receiving portions, braces secured across said inner portions from the inner to the outer faces thereof, said frame having continuous outer beads extending along said open portions, sashes mounted in the guides, removable jamb sections mounted in the sides of the frame at said open portions and

forming continuations of the guides of the frame, and means to detachably secure the jamb sections to the inner ends of the braces at the inside of the frame, said jamb sections having interfitting connection with the frame at and inwardly of the outer beads. 25

7. In a window construction, a casing having inner, outer and parting strips forming sash guides, sashes slideable in said guides and having interlocking portions, the sides of the casing at the inside having cut-outs enlarging inwardly and adapted to accommodate the sashes between the top and bottom portions thereof, and tapered jamb units adapted to fit said cut-outs and removably secured therein, said jamb units having strips and guides corresponding to those of the casing. 30 35

SAMUEL A. MENCZER.
